DESIGN FOR A LITURGICAL FLOUNCING OR SIMILAR ARTICLE

Otto Frei, New York, N. Y.

Application July 27, 1945, Serial No. 120,991

Term of patent 7 years

(Cl. D47—6)

To all whom it may concern:

Be it known that I, Otto Frei, a citizen of the United States of America, residing in New York city, county of New York, and State of New York, have invented a new, original, and ornamental Design for a Liturgical Flouncing or Similar Article, of which the following is a specification, reference being had to the accompanying drawing forming part thereof.

In the drawing the figure is a plan view of a piece of liturgical flouncing embodying the design.

The fabric upon which the design is embroidered is transparent and has been shown against a dark background in order to bring out the design. The design is repeated in regular succession longitudinally of the fabric. The portion of the flouncing above that shown in the drawing is plain transparent fabric.

I claim:

The ornamental design for a liturgical flouncing or similar article, substantially as shown and described.

OTTO FREI.
